CLAIM

The ornamental design for the pivot unit for gripper systems, as shown.

DESCRIPTION

FIG. 1 shows a top, front, right view of the unit in accordance with the invention;

FIG. 2 shows a top, front view of the unit in accordance with the invention;

FIG. 3 shows a top, left view of the unit in accordance with the invention;

FIG. 4 shows a top, back view of the unit in accordance with the invention;

FIG. 5 shows a top view of the unit in accordance with the invention;

FIG. 6 shows a bottom, front, left view of the unit in accordance with the invention; and,

FIG. 7 shows a bottom view of the unit in accordance with the invention;

1 Claim, 4 Drawing Sheets
